UNITED STATES PATENT OFFICE.

WILLIAM F. KELLY, OF SYRACUSE, NEW YORK.

SCREW-STEM LUBRICATOR.

1,367,482.

Specification of Letters Patent.

Patented Feb. 1, 1921.

Application filed June 25, 1919. Serial No. 306,528.

To all whom it may concern:

Be it known that I, WILLIAM F. KELLY, a citizen of the United States, residing at Syracuse, in the county of Onondaga and 5 State of New York, have invented a new and useful Screw-Stem Lubricator, of which the following is a specification.

The device forming the subject matter of this application is a lubricator adapted to be 10 applied to rotating members, and one object of the invention is to provide novel means whereby the flow of oil from container may be regulated through the instrumentality of a valve and means for adjusting the 15 movement of the valve. Another object of the invention is to improve the construction of the container portion of the lubricator.

It is within the province of the disclosure 20 to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within 25 the scope of what is claimed, changes in the precise embodiment of the invention shown can be made without departing from the spirit of the invention.

In the accompanying drawings:—

Figure 1 shows in side elevation, a lubricator constructed in accordance with the invention; Fig. 2 is a longitudinal section wherein parts have been left in elevation; Fig. 3 is a cross section on the line 3—3 of Fig. 1; and Fig. 4 is a fragmental longitudinal section showing the filling plug and attendant parts.

In carrying out the invention there is provided a container, denoted generally by the numeral 1. The container 1 comprises 45 a head 2 having a marginal flange 3, the head being supplied with a threaded axial opening 4, and with a threaded opening 5, located to one side of the opening 4. The container 1 embodies a foot 6 having a marginal flange 7 and a neck 8 including a reduced part 9 externally threaded as shown at 50 to accommodate a lock nut 11, the lock nut constituting means whereby the container may be held on a pulley or other rotating part. The bore of the neck 8 is denoted by the numeral 29 and is reduced at

its lower end to form an opening 12. At the inner end of the opening 12, a concaved seat 14 is fashioned. Gaskets 15 abut against the head 2, within the contour of the flange 3, 60 and against the foot 6, within the contour of the flange 7. A tubular body 16, preferably made of glass, is provided, the ends of the body being received within the flanges 3 and 7, the extremities of the body abutting 65 against the gaskets 15. The head 2 is connected with the foot 6 by means of any desired number of screws 17 having heads engaging the member 2, the screws being threaded into the foot 7. Obviously, the 70 screws 17 serve to bind the head 2 and the foot 6 on the gaskets 15, thereby rendering the container 1 oil-tight and air-tight.

A ball valve 18 is located in the bore 29 of the neck 8 of the foot 6 and is adapted 75 to be received in the seat 14. The travel of the ball valve 18 longitudinally of the bore 29 is adjusted by means of a member 19 including a foot 20 having a concavity or recess 21 shaped to approximate the contour 80 of the ball 18. The adjusting member 19 is threaded into the head 2 and is held in adjusted positions by means of a lock nut 23, carried by the threaded portions 2 of the adjusting member, externally of the head 2, 85 and adapted to bear upon the head 2. The adjusting member 19 carries, externally of the container 1, a finger piece 24 which, ordinarily, is mounted on the adjusting member after the adjusting member has been threaded 90 into the head 2.

A screw plug 25 is threaded into the opening 5 of the member 2 and is provided at its upper end with an enlarged head 26. The screw 25 has a shoulder 27, located inwardly of the head 26. A washer 28 surrounds a portion of the screw 25 and abuts against the shoulder 27. A flexible element 30, such as a chain, is attached to the inner end of the screw plug 25 and terminates in 100 an enlargement 31, such as a ring, the diameter of the ring 31 being greater than the diameter of the threaded opening 5 in the head 2.

In practical operation, the ball valve 18 105 reciprocates in the bore 29, the amount of oil fed through the opening 12 being regulated by the extent of travel of the ball. The throw of the ball, in turn, may be adjusted by advancing or retracting the member 19. 110 Since the member 19 is threaded at 22 into the head 2, the adjusting member may be

rotated readily by means of the part 24, and when the desired adjustment has been attained, the member 19 may be held in place by advancing the lock nut 23 until the same 5 bears against the head 2. The opening 4 is closed hermetically by the threaded portion of the adjusting member 19 and by the lock nut 22. The screw plug 25 may be advanced until the washer 28 is bound between 10 the shoulder 27 and head 2, a hermetic closure of the opening 5 being effected. Since the washer 28 is spaced from the head 26 by the shoulder 27, the head 26 is always accessible, so that the screw may be threaded 15 into the head 2 without difficulty, and be removed from the head, with equal facility. The ring 31, being larger in diameter than the opening 5, prevents the screw plug 25 from being detached completely from the 20 head 2, when the plug is threaded out of the opening 5, during the process of filling the container. Since the adjusting member 19 is supplied at its inner end with the enlarged 25 foot 20, the oil is prevented from having too rapid movement in the bore 29 and, at the same time, an adequate surface is afforded for contact with the ball valve 18, when the later reciprocates in the bore 29.

The foot 20 constitutes a baffle which, 30 while permitting the lubricant to flow into the outer portion of the stem 9, is adapted to prevent the lubricant from being emptied back into the chamber 10 by the motion imparted to the lubricator by the machine part 35 to which it is attached, whereby to insure the feeding of the lubricant to the bearing.

Having thus described the invention, what 40 is claimed is:—

1. A lubricator comprising a closed chamber, a hollow stem communicating with said chamber and extending downwardly from the bottom thereof, said stem being of con-

siderable length and having the lower end of its bore reduced, a valve seat formed in the shoulder provided by the reduction of the 45 bore of said stem, a ball valve normally resting upon said seat, a rod having threaded connection with the top of the chamber and extending through the chamber into said stem, the diameter of said rod being considerably less than the diameter of the bore of said stem, and a head formed on the lower end of said rod having a diameter greater than the diameter of said rod and less than the diameter of the bore of said stem and 55 provided in its under face with a recess adapted to receive said ball when it is forced from its seat, said rod being adjustable to regulate the distance of the travel of said ball from said seat. 60

2. A lubricator comprising a closed chamber, a hollow stem extending from and communicating with said chamber, a valve seat within said stem adjacent the outer end thereof, a ball valve adapted to be moved on 65 to and off of said seat by the motion imparted to the lubricator by the machine part to which it is connected, and a combined baffle and stop located within said stem beyond said chamber and inwardly of said 70 valve seat and adapted to prevent the motion of the lubricator from emptying the lubricant between said baffle and stop and said valve seat back into said chamber and also adapted to control the movement of said 75 valve in a direction away from said seat.

In testimony that I claim the foregoing as my own, I have hereto affixed my signature in the presence of two witnesses.

WILLIAM F. KELLY.
